UNITED STATES PATENT OFFICE.

JOHN W. WIEDEY, OF BALTIMORE, MARYLAND.

LAMP-SOCKET.

1,272,163.

Specification of Letters Patent.

Patented July 9, 1918.

Application filed June 3, 1916. Serial No. 101,551.

To all whom it may concern:

Be it known that I, JOHN W. WIEDEY, a citizen of the United States, residing at Baltimore, in the State of Maryland, have invented new and useful Improvements in Lamp-Sockets, of which the following is a specification.

This invention relates to an electric lamp socket and has for its primary object to simplify the switch construction while at the same time insuring perfect electrical connections.

An object of the invention is to provide a switch element of such a character that only a very limited movement is necessary to open and close the circuit.

Another object of the invention is the novel manner of constructing and associating the switch element with the other elements of the socket so that wear can be readily taken up so as to insure good electrical connections at all times.

Besides the above my invention is distinguished in the use of a single rotary element mounted for movement toward and away from one of the contacts of the socket and capable of exerting great pressure so as to materially decrease the resistivity to the passage of electrical current.

The invention will be better understood from the following detailed description taken in connection with the accompanying drawing wherein a preferred embodiment is illustrated and the features of novelty including all of the above mentioned and various others will be thereafter pointed out in the appended claim.

In the drawing:

Figure 1 is a vertical sectional view of one form of socket.

Fig. 2 is a vertical sectional view of a modified form of my invention.

Fig. 3 is a side elevation of the plug.

Referring to the drawing, the numeral 1 designates the shell socket having a screw threaded boss 2 and interiorly arranged threads 3 of a formation to receive the plug of the lamp. Fitting within the upper portion of the casing and provided with an annular flange 4 resting upon the top edge of the casing is a plug 5. This plug 5 supports a pair of contacts or conductors 6 and 7, the latter having one end portion completely inclosed in the plug 5 while the former extends completely through the plug and has its lower terminal flattened so as to engage

the central electrode of the lamp as illustrated at 8. In the preferred form of my invention the contacts 6 and 7 project a certain distance beyond the plug so as to be inserted into a pair of sockets in a manner well known. An auxiliary casing 9 has screw threaded engagement with the boss 2 and completely closes the exterior surface of the casing 1 with a portion extending over the plug 5 so as to clamp the flange 4 between the casings. The casing and plug are each provided with an opening 10 while the casing 1 is provided with a threaded opening 11. These openings are arranged in alinement, and threaded into the opening 11 is a screw 12 having a knurled head 13. At this point I wish to call attention to the fact that to insure the proper registration between the openings I provide a pin 14 mounted within the casing 9 and engaging the plug 5.

From this arrangement it will be seen that very slight pressure upon the head 13 is capable of giving movement to the screw so that the same may be forced into engagement with the contact 7. Very slight movement of the screw will cause the making and breaking of the circuit while at the same time the screw is capable of exerting great pressure upon the casing 1 and contact 7 for insuring a good electrical connection.

The modified form of my invention is identical with that just described with the exception that the contacts 15 and 16 have threaded thereon nuts 17 by means of which the usual conductors may be secured.

It is to be understood that while all of the several features of my improved lamp socket have special coöperation with one another and together constitute a particularly effective device for the purpose in view, certain of these features may be applied in other relations such as the manner of associating the casing with the plug and I therefore desire to cover the combination present in the several parts of my improved device whether employed in the general organization shown or elsewhere.

What I claim is:

A lamp socket comprising a conductive shell socket threaded internally for a portion of its length adjacent the lamp receiving end, an insulating plug provided with an opening in the side thereof mounted in the end of the shell socket and formed with a lateral circumferential flange engaging

the end of the socket, a casing provided with an opening in the ends thereof to register with the opening in the side of the plug, said casing encircling the socket and having threaded engagement therewith, a pin mounted in the casing to insure proper registrations between the respective openings, said casing holding the plug in engagement with the socket, a pair of leads embedded in

10 said plug, one of the leads having an extremity positioned to engage the central electrode of the lamp, and a headed screw mounted for movement through the casing, 15 socket and plug toward and away from the other lead.

In testimony whereof I affix my signature.

JOHN W. WIEDEY.
